SUSPENDED ROTATABLE RACK

Samuel J. Alexander, Los Angeles, Calif.
Application June 6, 1956, Serial No. 41,792

Term of patent 3½ years

(Cl. D44—29)

Fig. 1 is a side elevational view of the suspended rotatable rack, showing my new design.

Fig. 2 is a top plan view of the suspended rotatable rack.

I claim:

The ornamental design for a suspended rotatable rack, as shown.
